CLAIM

The ornamental design for a remote control stand, as shown and described.

DESCRIPTION

FIG. 1 is a front, right side, and top perspective view of a remote control stand showing my new design;

FIG. 2 is a front elevational view;

FIG. 3 is a left side elevational view;

FIG. 4 is a top plan view;

FIG. 5 is a bottom plan view;

FIG. 6 is a rear elevational view;

FIG. 7 is a front, right side, and top perspective view of a second embodiment of the stand shown in FIG. 1;

FIG. 8 is a front elevational view;

FIG. 9 is a left side elevational view;

FIG. 10 is a top plan view;

FIG. 11 is a bottom plan view; and,

FIG. 12 is a rear elevational view thereof.

FIGS. 2-6 and 8-12 have been shown on an enlarged scale with respect to FIGS. 1 and 7.
